UNITED STATES PATENT OFFICE.

JOHN ROWLAND BROWN, OF CLEVELAND, OHIO, ASSIGNOR TO THE OHIO BRASS COMPANY, OF MANSFIELD, OHIO, A CORPORATION OF NEW JERSEY.

DESIGN FOR A RAIL-BOND TERMINAL.

58,016.

Specification for Design.

Patented May 31, 1921.

Application filed August 9, 1920. Serial No. 402,441. Term of patent 14 years.

To all whom it may concern:

Be it known that I, JOHN ROWLAND BROWN, a citizen of the United States, residing in the city of Cleveland and the State of Ohio, have invented a new, original, and ornamental Design for an Electric Rail-Bond Terminal Used in Electrically Connecting Adjacent Rail Ends, of which the following is a specification, reference being had to the accompanying drawing, forming part thereof, in which—

Figure 1 is a side elevation; Fig. 2 is a part elevation taken on a side at right angle to that of Fig. 1; Fig. 3 is a top plan view and Fig. 4 is a bottom plan view.

As the terminal is used in connection with a conductor which is composed of a single or plurality of parts, the conductor is merely indicated by the dotted line as projecting from one end of the terminal and there broken off.

I claim—

The ornamental design for a rail bond terminal as shown.

In testimony whereof I have affixed my signature hereto.

JOHN ROWLAND BROWN.
